UNITED STATES PATENT OFFICE.

WILLIAM STEPHENS, OF SOMERVILLE, MASSACHUSETTS, ASSIGNOR TO SAMUEL STEPHENS AND WICKERSHAM QUOIN COMPANY, OF BOSTON, MASSACHUSETTS, A CORPORATION OF MASSACHUSETTS.

COMPOSING-ROOM CABINET.

Application filed June 5, 1926. Serial No. 113,887.

My invention relates to composing room equipment and more particularly aims to provide an improved type cabinet or cabinet top for use by compositors.

5 In the accompanying drawings illustrating by way of example an embodiment of certain forms of my invention:—

Fig. 1 is a front elevation of a composing room cabinet in accordance with one 10 form of the invention;

Fig. 2 is a plan of the same;

Fig. 3 is an end view of the cabinet top of Figs. 1 and 2; and

15 Fig. 4 is a view similar to Fig. 3 of a modified form of top.

Referring more particularly to the drawings, the body 1 of the type cabinet may be of any suitable standard or other form comprising one, two or more tiers of type cases or drawers, two tiers being shown in Fig. 20 1. The tiers of type cases obviously may be included in a single body, as illustrated, or two or more structurally separate tiers may be placed together for use as a unit.

25 Type cabinets of this general nature are customarily arranged in a composing room in alleys, one cabinet in back of another, with sufficient space between successive cabinets for a compositor or make-up man to work. The top of each cabinet generally is arranged to provide working space for the 30 materials with which a compositor is engaged during any particular composing job, such as his copy, the galley, etc., and also to give some storage room for leads, slugs, or 35 spacing material. Such storage space is customarily located on the same side of the cabinet with the job and blank cases or type drawers, while the working space is at the 40 opposite or working side of the cabinet top.

Thus each compositor works between two cabinets, having his copy, etc. at the working side of one cabinet, facing him, and having his material supplies in back of him, at 45 the adjacent rear side of the second cabinet.

Such arrangement requires the compositor frequently to turn from one cabinet to the other, to obtain the spacing materials, leads, 50 slugs, etc. Moreover, where a plurality of cabinets having tops of the type mentioned are arranged in alleys, there will be at one end of the alley a cabinet having its working side exposed, and with no opposing tier

of cases or material storage space, while at 55 the other end of the alley will be a tier of type cases and material storage space, with no corresponding working space.

My invention contemplates a working top having all its various elements readily accessible from the same side; desirably including a work-bank and suitable racks and cases for leads, slugs, or other spacing materials, all preferably on the side of the cabinet body with the type cases. A cabinet top constructed and arranged in accordance with my invention is particularly adapted for use to complete a row of cabinets, or against a wall, or for positioning back to back in pairs.

Referring again to the drawings, the cabinet or working top includes a base portion 2 adapted to seat upon the top of the cabinet body, a substantially vertical, closed rear wall 3, and side or end walls 4, 4. Said top, including the parts to be described, may be of any suitable material, such as wood, steel, or a combination of wood and steel. At the front of the cabinet top, facing the 50 compositor is a shelf or work bank 5 having a ledge or rib 6 along its forward and outer edge and extending rearwardly sufficiently to provide ample space for receiving the materials with which the compositor is working.

Means is provided for holding leads and slugs, illustrated as a rack 7, herein to the rear of and at a level above the work bank. Said rack comprises a plurality of front opening, vertically elongated compartments 80 8 which may extend back to the rear wall 3 of the cabinet top. Any desired number of such compartments may be provided and in the present form I have shown in said lead and slug rack sufficient compartments to hold an alley supply of leads of lengths from 10 to 50 by ems, and slugs of lengths from 10 to 40 by ems. This division of the vertical compartments as between leads and slugs obviously might be reversed, or otherwise arranged. The provision of vertical opening compartments, relatively narrow but deep, permits the storing of the extensive supply of leads and slugs mentioned. The compartments are desirably numbered 105 with the appropriate size of lead or slug, as indicated at 9.

In addition to said lead and slug rack,

holding the longer spacing materials, I preferably provide a case or tray for the short length leads and slugs, such spacing material case being indicated at 10, herein above and 5 directly to the rear of the mouth of the lead and slug rack 4. It may include a tray proper which is removable from the cabinet top, as illustrated, or the various compartments may be built into the cabinet top.

10 Said compartments of the spacing material case 10 may be of any desired size, number, and arrangement but preferably and, as shown, top opening compartments are provided for all sizes of thin brass and copper 15 spaces, leads in lengths from 1 to $9\frac{1}{2}$ ems by ems, and for six sizes of spaces and quads. The spacing material case illustrated comprises four rows of compartments, the two rear rows 11, 11 accommodating the spaces 20 and quads, with six compartments for each of six sizes, the third row from the rear, 12, having the short length leads, and the front row 13 receiving the thin brass and copper spaces. Said spacing material case or tray 25 is desirably supported in a somewhat inclined position substantially as illustrated, to assist the compositor in locating and selecting the materials from it, appropriate numbering or index being provided, as 30 at 14.

In the form shown in Figs. 1 to 3 the cabinet top includes in addition to the work bank 5, lead and slug rack 7, and the spacing material case 10, each extending substantially the full length of the cabinet, a bin 35 15 having a row of front opening compartments for metal quotations, metal or iron furniture, or the like. Said bin 15 may constitute a built-in portion of the cabinet top, 40 or be constructed as a removable unit, preferably located over and to the rear of the spacing material case and vertically above the rear portions of the compartments 8 of the lead and slug rack. It may be arranged 45 to hold any desired number of quotations and, as illustrated, includes fourteen compartments which may receive a corresponding number of sizes of quotations, for example, the following standard sizes—2 x 3; 50 2 x 4; 2 x 5; 2 x 6; 3 x 3; 3 x 4; 3 x 5; 3 x 6; 4 x 4; 4 x 5; 4 x 6; 5 x 5; 5 x 6; 6 x 6. The individual bins may be appropriately numbered as illustrated at 16.

From the above description, taken in connection with the drawings, it will be understood that I have provided a type cabinet top having a closed rear face and in which all of the several elements are accessible from the front or working side. These elements 55 may be arranged otherwise than as illustrated, particularly with regard to their disposition from front to rear of the cabinet top. For example, the lead and slug rack might 60 be at the extreme front face of the cabinet top and the work-bank positioned above it,

or the position of the spacing material case and the work-bank might be interchanged. In some instances it is not necessary to have the quotation supply immediately in front of the compositor and in such case the bin 70 15 might be omitted. Such a modified construction is illustrated in Fig. 4 wherein the cabinet top includes a work-bank 5', lead and slug rack 7' and spacing material case 10'. 75

A cabinet top such as described, and which is adaptable to any standard or other cabinet enables a compositor to work at, and obtain all necessary materials from, one side of a single cabinet. It thus increases the efficiency in a composing room and in addition makes it possible to employ floor space otherwise not available for this purpose, such as against walls or at the ends of otherwise incomplete rows of cabinets of the divided type heretofore employed. 80 85 90

My invention is not limited to the particular embodiments thereof shown and described herein, its scope being set forth in the following claims. 95

Claims:

1. In combination with a type cabinet having one or more tiers of type cases accessible from the cabinet front, a working top for said cabinet comprising a base 95 adapted to seat on the cabinet, a permanently positioned, exposed work-bank, a lead and slug rack, and a spacing material case, said work-bank, rack and case being all positioned for access from the same side of the cabinet and being so mounted on said case that said side is the cabinet front, whereby the tiers of type cases and all of said elements of the top are readily accessible to a compositor facing the cabinet. 100 105 110 115 120

2. A working top for a type cabinet having one or more tiers of type cases comprising, in combination, a base, a rear wall and end walls, and a working front, said front being provided with a work-bank, a lead 11 115 and slug rack, and a spacing material case, each extending longitudinally substantially the full distance between said end walls and all readily accessible from said front and working side. 120 125 130

3. In combination with a type cabinet having one or more tiers of type cases accessible from the cabinet front, a working top for said cabinet comprising a base adapted to seat on the cabinet, a longitudinal work-bank extending substantially the full length of said base, a lead and slug rack, a spacing material case, and a quotation bin, said work-bank, rack, case and bin being all positioned for access from the same side 12 125 130 of the cabinet and being so mounted on said base that said side is the cabinet front.

4. A working top for a type cabinet, comprising, in combination, a base, a rear wall and end walls, and a working front, said 13

front being provided with a work-bank extending substantially the full length of said base, a longitudinally extending lead and slug rack, and a longitudinally extending spacing material case, said work-bank, lead and slug rack, and spacing material case being all readily accessible from said front and working side.

5. In a top for a type cabinet, a base, a rear wall, and end walls, an exposed work-bank substantially wholly within the confines of said base, a longitudinal lead and slug rack spaced vertically from said work-bank, and a spacing material case on a level different from that of said work bank and said lead and slug rack.

6. In combination with a type cabinet having one or more tiers of type cases accessible from the cabinet front, a working top for said cabinet comprising a base adapted to seat on the cabinet, an inclined work-bank extending the length of the top, a multiplicity of front opening compartments side by side forming a rack for leads and slugs, and a series of top opening compartments arranged in a plurality of

rows lengthwise the top and affording storage for thin brass and copper spaces, spaces and quads, each of said elements positioned for ready access by a compositor at the cabinet front. 30

7. In combination with a type cabinet having one or more tiers of type cases accessible from the cabinet front, a working top for said cabinet comprising a base 35 adapted to seat on the cabinet, an inclined work-bank extending the length of the top, a multiplicity of front opening compartments side by side forming a rack for leads and slugs, a series of top opening compartments arranged in a plurality of rows lengthwise the top and affording storage for thin brass and copper spaces, spaces and quads, and a longitudinal row of front opening compartments constituting a bin 40 45 for quotations, each of said elements positioned for ready access by a compositor at the cabinet front.

In testimony whereof, I have signed my name to this specification.

WILLIAM STEPHENS.

Certificate of Correction.

Patent No. 1,630,678.

Granted May 31, 1927, to

WILLIAM STEPHENS.

It is hereby certified that error appears in the printed specification of the above-numbered patent requiring correction as follows: Page 2, line 101, claim 1, for the word "case" read *base*; and that the said Letters Patent should be read with this correction therein that the same may conform to the record of the case in the Patent Office.

Signed and sealed this 21st day of June, A. D. 1927.

[SEAL.]

M. J. MOORE,
Acting Commissioner of Patents.
